FIG. 2.

UNITED STATES PATENT OFFICE

2,497,372

PLAYGROUND EQUIPMENT

Willie E. Pricer, Amarillo, Tex.

Application July 25, 1947, Serial No. 763,549

3 Claims. (Cl. 272—33)

1

This invention relates to a novel construction of multiple playground equipment and more particularly to a combination swing and merry-go-round which is occupant propelled.

More particularly, it is an object of the present invention to provide a combination swing and merry-go-round having a connection therebetween whereby the swing will be propelled by the occupant thereof for transmitting motion to the merry-go-round.

Still a further object of the invention is to provide a novel means whereby the oscillating motion transmitted by the swing is converted into a rotary motion for transmission to the merry-go-round.

Various other objects and advantages of the invention will hereinafter become more fully apparent from the following description of the drawings, illustrating a preferred embodiment thereof, and wherein:

Figure 1 is a perspective view of a preferred embodiment of the playground equipment;

Figure 2 is an enlarged longitudinal sectional view through the gear housing thereof;

Figure 3 is a cross sectional view taken substantially along a plane as indicated by the line 3—3 of Figure 2;

Figure 4 is a cross sectional view taken substantially along a plane as indicated by the line 4—4 of Figure 2, and

Figure 5 is an enlarged fragmentary cross sectional view of a portion of the clutch.

Referring more specifically to the drawings, the improved playground equipment in its entirety is designated generally 7 and includes a swing, designated generally 8 and a merry-go-round, designated generally 9.

The swing 8 includes a supporting frame, designated generally 10 having upwardly and inwardly inclined legs 11 at the corners thereof and which are connected at their upper ends to corresponding longitudinal side members 12 forming a part of the frame top. The side members 12 are connected at corresponding ends thereof by a cross member or rod 13 which joins with the upper ends of two of the legs 11. The upper ends of the other two legs 11 are connected to the opposite ends of the side bars 12 by bearing members 14 which are interposed therebetween and which may be suitably connected to or formed integral with said last mentioned ends of the side members 12 and the two last mentioned legs 11. The bearing members 14 are disposed in transverse alignment for journaling an end 15 of a shaft 16, which end 15 forms the other cross member

2

of the frame top, but which differs from the cross member 13 in that it is rotatable relatively to the frame 10.

The swing 8 includes two pairs of depending levers 17 and 18. The upper ends of the levers 17 are keyed by collars 19 to the shaft portion 15 between the bearings 14 and the upper ends of the levers 18 are provided with aligned bearing portions 20 which are journaled on the cross member 13. The lower ends of the pairs of levers 17 and 18 are connected pivotally to the ends of a platform, designated generally 21 including substantially parallel side rails 22 which are journaled at their ends to individual levers 17 and 18 by cross rods or shafts 23, one of which extends through and is journaled in the lower ends of the levers 17 and connected to corresponding ends of the side rails 22 and the other of which similarly extends through and is journaled in the lower ends of the levers 18 and connected to the opposite ends of the side rails 22. The platform 21 also includes two cross rails or rods 24, one of which is disposed adjacent to but spaced from each end of the platform 21.

An occupant supporting seat 25 is supported between each of the pairs of levers 17 and 18, above but adjacent their lower ends, said seat 25 having pins or stub shafts 26 projecting from the ends thereof and which extend through and are journaled in the levers 17 and 18 for swivelly mounting the seats relatively thereto. The seats 25 are connected by a connecting bar 27 which extends therebetween and is connected at its ends to the undersides of said seats and a lever 28 is pivotally connected intermediate of its ends to the connecting bar 27 adjacent each seat 25 and approximately above the cross rod 24, disposed adjacent thereto. The lower ends of the levers 28 are pivotally connected to or journaled on the intermediate portions of the cross rods 24 and the upper ends of said levers 28 are provided with cross handles 29 adapted to be engaged by the occupants of the seats 25 who sit facing inwardly or toward one another with their feet upon the adjacent cross rod 24 and with their hands engaging the handle 29 so that by the execution of a backward and forward or oscillating motion on the handles 29 and accordingly on the upper ends of the levers 28, it will be readily apparent that the platform 21 and the levers 17 and 18 will be caused to swing as a unit longitudinally in the frame 10 and which will also cause the shaft 16 to be oscillated in unison therewith.

The merry-go-round 9 includes a top portion 30

having depending and diverging legs 31 extending from the corners thereof and combining therewith to form the merry-go-round frame. A thrust bearing 32 is fixedly disposed on the supporting surface of the legs 31 for journaling the lower end of an upwardly extending shaft 33 which is disposed substantially centrally of the merry-go-round frame and the upper end of which extends through and is journaled in a bearing 34 in the central portion of the frame top 30.

A gear housing having an open flanged bottom is secured by fastenings 35 which extend through the flanges or ears 36 thereof and into the frame top 30, for detachably mounting said housing thereon. Said gear housing, designated generally 37, is provided with bearings 38 in the ends thereof and in which the opposite end of the shaft 16 is journaled so that said shaft extends longitudinally through the gear housing 37. A bearing 39 is journaled on the shaft 16 adjacent each end of the gear housing 37 and on the inner side thereof and each of said bearings 39 is provided with a radially projecting flange 40 at its inner end. The flanges 40 are connected by means of fastenings 41 to annular bevel gears 42 and 43 which are disposed in opposed relationship to one another and which mesh with diametrically opposed portions of a large upwardly facing bevel gear 44 which is likewise disposed in the housing 37 and keyed to the upper end of the shaft 33.

The bevel gears 42 and 43 are provided with pawl and ratchet clutch means 45 and 46, respectively, each of which includes a collar 47 which is splined or keyed at 48 to the shaft 16 so that said collars 47 are disposed within and concentric of the annular bevel gears 42 and 43. Each of the collars 47 is provided with at least one and preferably two outwardly opening recesses 49 in the periphery thereof and the beds of which recesses are generally arcuately shaped. If the collars 47 are provided with two recesses 49, such recesses are preferably disposed in diametrically opposed relationship and each of said recesses has a pin or shaft 50 extending transversely therethrough to provide a pivot for a pawl 51 which is thereby pivotally mounted relatively to its collar 47 for swinging movement in its recess 49 and which has a longer end projecting outwardly therefrom. The inner annular faces of the bevel gears 42 and 43 are provided with teeth 52 arranged circumferentially therearound and which face in the same direction and each of which includes an inclined face and a substantially radially disposed face. The pawls 51 are provided with rounded rear sides for engagement with the inclined faces of the teeth 52 and with substantially straight and radial opposite sides for engagement with the substantially radially disposed faces of the teeth 52. A leaf spring 53 has one end thereof fixedly secured by a fastening 54 in each recess 49 and has its free end projecting outwardly therefrom and bearing against the substantially straight edge of its pawl 51 for urging the pawl to turn relatively to its collar 47 in a counterclockwise direction, relatively to its hub 47, as seen looking toward the inner end of the hub or collar.

Referring to Figure 1, the shaft 33 has a collar 55 keyed thereto and adjacent the lower end thereof from which projects a plurality of radial supporting arms 56 which are connected intermediate of their ends by an annular brace 57. A plurality of occupant supporting seats 58 are mounted outwardly of the annular brace 57, each

of said seats 58 having one side thereof supported by a portion of the annular brace 57 and the back thereof supported by the outer end of one of the radial arms 56. The seats 58 and radial arms 56 are disposed so that they may rotate freely within the merry-go-round frame and between the legs 31 thereof.

From the foregoing it will be readily apparent that when the swing 8 is occupied and operated by one or two occupants that the shaft 16 will be oscillated thereby. As the shaft 16 oscillates in a clockwise direction, as seen in Figures 3 and 5, the hub or collar 47 of the clutch 45 and which is associated with the bevel gear 42 will likewise turn in a clockwise direction causing the straight edges of the pawls 51 thereof by engagement with the radial faces of the teeth 52 to turn the bevel gear 42 also in a clockwise direction for rotating the large bevel gear 44 and the shaft 33 in the direction as indicated by the arrow 59 in Figure 2. On the opposite or return swing of the swing structure and by which the shaft 16 is rotated in the opposite direction or counterclockwise, as seen in Figure 3, the rounded back edges of the pawls 51 of the clutch 45 will ride over the inclined, opposite sides of the teeth 52 so that said hub 47 thereof will turn with the shaft 16 counterclockwise and relatively to the gear 42. During this counterclockwise rotation of the shaft 16, the pawls 51 of the collar 47 of clutch 46 will rotate the bevel gear 43 with the shaft 16 due to the fact that the pawls 51 of the clutch 46 will have their straight edges bearing against the radial faces of the teeth 52 of the bevel gear 43 so that the bevel gear 43 will rotate counterclockwise with the shaft 16, as seen in Figure 4 for turning the bevel gear 44 and shaft 33 in the direction as indicated by the arrow 59 and while the clutch 45 is disengaged, as previously described. Likewise, when the shaft 16 is rotating clockwise, as seen in Figure 3 and the clutch 45 is engaged, as previously described, the rounded back edges of the pawls 51 of the clutch 46 will be riding over the inclined edges of the teeth 52 of gear 43 so that the clutch 46 will be disengaged. It will thus readily apparent that the bevel gear 44 and shaft 43 will be rotated in the same direction and substantially constantly while the swing 8 is in operation and it will likewise be readily obvious that this rotation of the shaft 33 will impart a rotation to the arms 56, brace 57 and seats 58 in the same direction.

Various modifications and changes are contemplated and may obviously be resorted to, without departing from the spirit or scope of the invention as hereinafter defined by the appended claims.

I claim as my invention:

1. In a combination playground equipment, a swing supporting structure, an occupant actuated and occupant supporting swing supported for oscillating movement by said swing supporting structure, a shaft fixed to the swing at the pivot thereof for oscillating movement with the swing, said shaft being journaled in the swing supporting structure, a merry-go-round spaced from the swing and having a centrally disposed upright driving shaft, a merry-go-round supporting structure supporting the merry-go-round and in which the upright driving shaft is journaled, gear means mounted on the merry-go-round supporting structure and connecting the first mentioned shaft to said merry-go-round driving shaft, and clutch means operatively connected

to the gear means for driving the upright driving shaft constantly in the same direction when the gear means is actuated by oscillation of the first mentioned shaft.

2. A combination playground equipment as in claim 1, said gear means including a large bevel gear keyed to the merry-go-round drive shaft, and opposed bevel gears mounted on and driven by the first mentioned shaft and meshing with diametrically opposed portions of the first mentioned bevel gear.

3. A combination playground equipment as in claim 1, said gear means including a large bevel gear keyed to the merry-go-round drive shaft, opposed bevel gears connected to the first mentioned shaft and meshing with diametrically opposed portions of the first mentioned bevel gear and said clutch means including a pawl and ratchet clutch associated with each of said last mentioned bevel gears, one of said clutches be-

ing arranged to drive the bevel gear thereof in one direction of oscillation of the first mentioned shaft, and the other clutch being constructed and arranged to drive its bevel gear when the first mentioned shaft is oscillating in the opposite direction.
